UNITED STATES PATENT OFFICE.

CHARLES F. SMITH, OF NEW BRITAIN, CONNECTICUT, ASSIGNOR TO THE LANDERS, FRARY & CLARK, OF SAME PLACE.

DESIGN FOR A KNIFE-HANDLE, &c.

SPECIFICATION forming part of Design No. 25,560, dated June 2, 1896.

Application filed April 25, 1896. Serial No. 589,049. Term of patent 7 years.

To all whom it may concern:

Be it known that I, CHARLES F. SMITH, a citizen of the United States, residing at New Britain, in the county of Hartford and State 5 of Connecticut, have invented and produced a new and original Design for Cutlery-Handles, of which the following is a specification, reference being had to the accompanying drawings, in which—

10 Figure 1 is a side elevation of a knife-handle, showing my design. Fig. 2 is a plan or edge view of the same.

15 My handle comprises a tang 3 of a knife or fork, the bolster 4, tip 5, and scales 6. It is oval in cross-section or end view and slightly tapering in side view, being the broadest at the butt.

20 The middle portion of the handle-scales is ornamented by an inlaid ornament consisting of a central circular hub 7, two transverse bars

or arms 8, projecting diametrically from said hub, and four curved bars or arms 9, extending in pairs from said central hub in curved lines to the edge of the scales. The arms in each pair, when taken together, form the segment of a circle, and these two segments are arranged with their convex sides facing each other, as shown. While the complete ornament shows only when the handle is seen in side view, it may be observed that the ends 25 of the transverse and curved bars 8 and 9 shew in plan or edge view, as in Fig. 2.

What I claim is—

25 The design for a cutlery-handle substantially as herein shown and described.

CHARLES F. SMITH.
